UNITED STATES PATENT OFFICE

FRANCIS C. ATWOOD, OF NEWTON, MASSACHUSETTS

METHOD OF AND APPARATUS FOR APPLYING A LIQUID COATING TO A SURFACE

Application filed July 13, 1929. Serial No. 378,060.

This invention relates to a method of and apparatus for applying a liquid coating to a surface. It lends themselves to the application of the present method.

One object of the invention is to provide a novel and highly efficient method of producing a decorative finish upon a rough surface, by which maximum contrast between the high lights and the depressions in the surface may be secured with a minimum amount of coating material.

Another object of the invention is to provide novel and efficient apparatus for practicing the present method, and by which the desired decorative finish may be applied to the surface with minimum labor and at minimum expense.

With these objects in view, and such others as may hereinafter appear, the invention consists in the method and apparatus and in the various structures, arrangements and combinations of parts hereinafter described and particularly defined in the claims at the end of this specification.

In the drawing illustrating the preferred apparatus for practicing the present invention, Fig. 1 is a vertical sectional view of a pressure squeegee; Fig. 2 is an enlarged detail with parts in section illustrating the detachable connection between the squeegee and the pressure chamber; Fig. 3 is a view partly in section and partly in elevation of a modification of the apparatus; and Fig. 4 is an end elevation of the squeegee connected to a discharge conduit through which the liquid coating may be supplied.

In general the present method is particularly suitable for finishing walls, ceilings, and other surfaces which may be provided with surface irregularities in any sort of design. These surface irregularities may be large or small and may be produced by manipulation of the plastic coating after the latter has been applied to the surface and before it has become set or hard. For example, the character of surface may be that produced by the well-known texturing plastics such as Craftex. Even the ordinary plaster surface comprising ordinary walls and ceilings possesses irregularities and a surface roughness which

It has heretofore been the practice in finishing walls and ceilings with Craftex and certain other texturing plastics to apply a liquid coating material, commonly referred to as a glaze, to the textured plastic surface, and then to wipe off with a cloth portions of the glaze from the highlights or raised portions of the rough textured surface in order that the depressions may be filled with glaze and the glaze removed from the highlights, thus bringing out the highlights and emphasizing the design or texture in the surface. The use of the cloth in wiping the glaze from the highlights not only leaves more or less of the glaze upon the highlights but also portions of the cloth extend down into the depressions and remove some of the glaze from the depressions so that the contrast between the highlights and depressions has not been as pronounced and emphatic as could be desired. This is particularly true when the surface irregularities are relatively small.

In accordance with the present invention, provision is made for wiping off the high lights in a manner such that the glaze is caused to flow into the depressions, filling the same, and also in such manner that the wiping device does not enter the depressions and does not remove any of the glaze therefrom. I have experienced particularly good results utilizing a rubber squeegee in wiping off the glaze from the high lights or raised portion of the rough or textured surface, such as a wall or ceiling. In addition considerable labor may be eliminated by utilizing the rubber squeegee in both applying and wiping the glaze to and from the surface, and in practice I have found it is necessary only to dip the squeegee in the glaze and pass it over the surface, and as a result of this single operation the glaze is applied to the surface, wiped from the highlights and forced to run down into the depressions, filling the same all in the single operation as the squeegee wet with the glaze is passed over the rough or textured surface. In this manner the distinction between the high lights and the depressions is brought out in a most emphatic

manner and the desired decorative effect is produced upon the surface in a most efficient and economical manner.

In practice the present method of wiping or of applying and wiping the glaze from the high lights of a textured or rough surface finds particular use in the production of so-called textured walls or ceilings. Nevertheless these methods may be used with advantage in producing decorative effects upon roughened surfaces of all sorts, and upon many different materials such for example as upon the roughened surface produced by embossing paper or similar sheet material, and in the manufacture of such sheet material the squeegee may and preferably will comprise a rubber doctor under which an embossed web of the paper or other material is passed and the glaze is applied to the sheet preparatory to its passage under the rubber doctor. This method of manufacturing an embossed or roughened paper sheet of itself forms no part of the present invention but forms the subject matter of a copending application Serial No. 375,185, filed July 1, 1929.

In order to facilitate the application of the glaze or other coating material in the practice of the present method, the squeegee is preferably constructed as illustrated in the drawing, wherein 10 represents the squeegee provided with a contacting surface 12 which is designed to pass over the high lights of the rough surface and to wipe the glaze therefrom into the depressions. The squeegee 10 is also provided with a reservoir 14 within the same connected by a number of passages 16 to the contacting surface 12, so that when the liquid glaze is supplied to the reservoir 14 it may be forced outwardly through the conduit or passages 16 and supply the contacting surface 12 with the glaze. With this construction, as the squeegee is passed over the surface, the glaze is applied by the squeegee and simultaneously wiped from the high lights.

In practice I prefer to construct the squeegee 10 of rubber which may be molded into the shape illustrated and which will also preferably be provided with a neck portion 20 having a coupling member 22 adapted to screw upon the discharge pipe of a pressure gun 24 of any usual or preferred type. I have herein illustrated such a gun as provided with a piston 26, a removable cover 30 through which the supply of liquid glaze may be introduced into the body of the gun. The cover 30 is provided with a boss 29 provided with a threaded hole through which a threaded shaft 28 is screwed so that upon rotation of the handle 32, the piston is forced downwardly operating to expel the liquid glaze from the gun and to cause it to fill the reservoir 14 within the squeegee and to pass outwardly through the small passages 16 to sup-

ply glaze upon the contacting surface of the squeegee.

The squeegee 10 may be connected directly to the discharge pipe of the gun in the manner illustrated in Fig. 1, or if desired it may be connected, as illustrated in Fig. 4, to a conduit 44 through which the liquid coating material may be forced under pressure from any suitable supply. For example, the conduit 44 may comprise the ordinary flexible hose commonly used in connection with pressure gun systems for supplying fluid under pressure.

In Fig. 3 I have illustrated a modified form of squeegee in which the squeegee may be made entirely of rubber and attached to a bulb 40 designed to be compressed to force the liquid glaze from within the bulb and from the reservoir 14, as will be apparent from an inspection of Fig. 3.

In using the illustrated apparatus the glaze may be simultaneously applied to the rough surface to be finished and wiped from the high lights by a single passage of the squeegee across the surface. This enables the coating material to be applied in a most efficient manner with minimum labor and with minimum loss of coating material, and the construction of squeegee is such as to overcome the difficulties above referred to which have been heretofore experienced involving the wiping of the glaze from the high lights by a cloth.

As used throughout the specification and claims, the word "glaze" is used with the intention of including those colored coatings commonly referred to as glaze, and also any other colored coatings which are capable of being used with advantage in the application of the present method in finishing different sorts of rough or irregular surfaces, and while I prefer to employ a rubber squeegee, other forms of squeegee may be used, preferably of a non-absorbent material.

While the preferred form of apparatus has been herein illustrated and described, it will be understood that the invention may be embodied in other forms within the scope of the following claims.

Having thus described the invention what is claimed is:—

1. The method of producing a decorative finish upon a rough wall or ceiling, which consists in applying to the surface a quantity of a liquid glaze from the operative edge of a pliable squeegee by manually passing the squeegee over the surface to thereby wipe the liquid glaze from the high-lights and into the depressions of the surface substantially simultaneously with the application of the glaze.

2. The method of producing a decorative finish upon a rough wall or ceiling, which consists in causing a quantity of a liquid glaze to accumulate along the operating edge of a rubber squeegee, manually passing the squeegee over and in contact with the surface to

apply the glaze to the surface and simultaneously wipe the glaze from the high-lights and into the depressions of the surface.

3. The method of producing a decorative
- 5 finish upon a rough wall or ceiling, which consists in applying a liquid glaze to the surface, and thereafter manually wiping the glaze from the high-lights by a pliable squeegee.
- 10 4. The method of producing a decorative finish upon a rough wall or ceiling, which consists in dipping a pliable squeegee into a bath of a liquid glaze and manually passing the squeegee over the rough surface to there-
- 15 by apply the glaze to the surface, and simultaneously wiping the glaze from the high-lights into the depressions.

In testimony whereof I have signed my name to this specification.
